ABSTRACT: A portable data recorder has punches movable between retracted and recording positions. Slides stacked along the direction of movement of the punches are movable transversely to the punches to control their movement. The slides have openings arranged so that when the openings in all slides in a stack are aligned a punch can pass through a stack to its recording position.

FIG 13

PORTABLE RECORDING

This invention relates to portable data recording apparatus of the type in which a plurality of slides are positioned in accordance with the input data and in turn control the recording elements.

Objects of the invention are to provide such apparatus that is highly reliable (e.g., by preventing deformation of the slides, minimizing operating friction, and reducing the number of functions that are dependent upon the variable abilities of human operators), has reduced power requirements, is easily operated (e.g., with semiautomatic facilities for handling the medium upon which the data is recorded), and is simple and inexpensive.

The invention features, in one aspect, recording elements movable between retracted and recording positions, slides stacked along the direction of movement of the recording elements movable generally transversely to the recording elements to control the movement of the recording elements, the slides having openings arranged so that when the openings in all slides in a stack are aligned a recording element can pass through the stack to its recording position, the recording elements contacting a slide only when nonalignment of openings prevents passage of the element to its recording position; and in another aspect slides controlling the movement of recording elements wherein a power solenoid moves the slides against spring biasing and additional solenoids operatively control members which move in and out of the paths of movement of slides to determine slide positions. In preferred embodiments the additional solenoids are smaller than the power solenoid and the operatively controlled members correspond to and interact with tabs on the slides (the members being at times in the paths of the tabs, at times out of contact with the tabs, and at times held out of the tab paths by the tabs themselves); each slide opening is larger than the cross section of any recording element associated therewith for passage therethrough to the recording position and a portion of each recording element when in its retracted position extends through an opening in at least one slide without contacting the slide; the actuator for the recording elements is motor driven and includes a pressure pad with a member mounted thereon having oblique surfaces and a roller driven by the motor along the oblique surfaces to in turn drive the pressure pad; and a card handling assembly is provided including a base, at least one roller mounted adjacent the base to contact a card (on which data is to be recorded) inserted under the roller, a torsion spring rotationally biasing the roller, and an abutment against which the card edge is forced by the biased roller after the card has been inserted.

Other objects, features, and advantages of the invention will be apparent from the following description of a preferred embodiment thereof, taken together with the drawings in which:

FIG. 1 is a perspective view of the apparatus;

FIG. 2 is a perspective view of a portion of the interior of the apparatus;

FIG. 3 is a perspective view of the motor and associated electrical contacts;

FIG. 4 is an exploded view otherwise similar to FIG. 2;

FIG. 5 is a fragmentary section taken from the side of one of the punches;

FIGS. 6-8 are fragmentary sections taken from above a slide, showing the slide in different positions;

FIGS. 9-11 are fragmentary sections similar to FIG. 5 but including the pressure pad area, showing the punches in different positions;

FIG. 12 is a block diagram of the electrical circuitry; and

FIG. 13 is a circuit diagram corresponding to FIG. 12.

The complete portable card punch unit is shown in FIG. 1 and includes housing 10 with removable side 12, and a nineteen conductor cable 16 electrically connecting the unit to a probe (not shown) for insertion into a meter to be read. Battery pack 18 is connected to the unit by cable 20. Printed circuit boards 22 control the major functions of the unit. Dials 24, controlling rotary four-contact binary coded decimal switches, are provided for manually setting on the unit the

reading of a meter not capable of automatic readout through the probe. Punch module 26, shown in detail in FIGS. 2-11, is mounted inside the housing.

Module 26 has punches 30 (FIG. 4) for punching a card to record the meter reading, decoding slides 32 and decoding solenoids 34 for controlling the punches in accordance with the meter reading, and a motor and cam operated pressure pad 36 for forceably moving the punches through their punching stroke.

Slides 32 are arranged in four stacks of four slides each, with two lower stacks side-by-side in grooves 42 and 44 of punch block 46, and two upper stacks side-by-side in grooves 48 and 50 of guide 52. Four prongs 56, carried by reset finger 60 connected to the core 62 of reset solenoid 64, fit through openings 58 at the left ends (as seen in FIG. 4) of the slides in the four stacks, respectively. Openings 58 are larger than the thickness of a prong 56, to allow slides 32 to move longitudinally relative to reset finger 60, as explained below.

Slides 32 are connected at their right ends to return springs 70 attached to bracket 71. Each slide has a laterally extending tab 72 near its right end, the tabs 72 on the respective slides being staggered as shown in FIG. 4. The slides have punch openings 74 spaced along their central portions, through which punches 30 pass. Openings 74 are larger than the cross section of a punch, so that the punches never touch the slides so long as the openings are properly aligned. Similar openings 47 are located in block 46. Trapper plate 80 is positioned above guide 52, and has openings 82 for the punches.

Die plate 92, having individual openings 91 for the punches, and base plate 94, are positioned below block 46 to receive the punch heads that punch through the card.

Anvil 94, plates 92 and 80, guide 52, and block 46 are held together by bolts 93, 95 in a subassembly that is stationary throughout the operation of the module.

Above plate 80 are located a pair of generally similar plates: punch retaining plate 96 with punch openings 98, and lockplate 100 with punch openings 102, the latter being free to slide longitudinally above plate 96 which holds it in place, and connected at its left end to solenoid 104 for control of its longitudinal position.

Punch spring cage 110 has punch openings 111 similar to openings 98 and 102, and is bolted to plate 96 from above by bolts 112. Pin plate 114 and pressure pad 36 are bolted to cage 110 from above. Pin plate 114 has small openings 118 for the pins 120 at the tops of the punches 30. Guide 52 has punch openings 54.

Guide pins 130 (FIG. 4) are mounted at the four corners of punch block 46 and extend upwardly through bushings 132 carried at the corners of cage 110 and are capped by nuts 134. Coil springs 136 surround pins 130. Cage 110, pressure pad 36, plate 114, and plates 96 and 100 are thus slidable as a unit on pins 130, toward (against springs 136) and away from block 46.

Cam 140 is mounted rigidly on top of pressure pad 36, and has a multiple pitch cam surface including horizontal portion 142, steeply inclined portion 144, and less steeply inclined portion 146.

Above cam 140 drawbar 150 is mounted for horizontal sliding movement on pins 152 extending through support bracket 154. Movement of drawbar 150 is controlled by levers 156 and 158 pivotally connected to each other at 160. The other end of lever 156 is pivoted to drawbar 150 at 162. Lever 158 is connected at its center to shaft 164 (FIGS. 2-4) driven through gears 165 and 166 by cycling motor 167 supported on bracket 168. Motor 167 is driven electrically by battery pack 18 through wires 170. Drawbar 150 carries roller 172 positioned to contact cam 140.

There are 40 punches 30, arranged in ten rows of four, with each row positioned with the punches passing through one aligned set of openings 111, 102, 98, 82, 54, 74, and 47. Each punch (FIGS. 5, 9-11) has a punch head 180, an intermediate reduced width neck 182 with curved sides 184, 186, an upwardly directed shoulder 190, and a tab 192 providing

shoulders 194 and 196. Pins 120 are at the tops of the punches, and carry coil springs 200 between washers 202 and 204. Neck 182 is located in openings 74 in slides 32 when pressure pad 36 is in its uppermost position (FIG. 9).

Sixteen decoding solenoids 34 are mounted in four groups of four above and below and at each side of slides 32 (one upper and one lower group are shown in FIG. 4, and two upper groups are shown in FIG. 2). The cores 35 of those solenoids are respectively adjacent the 16 staggered tabs 72. The solenoids are wired to printed circuit boards 210, 212.

The size of openings 58, the travel of finger 60, and the positioning of solenoids 34 and flanges 72 are such that when finger 60 is fully retracted upon actuation of reset solenoid 64 (all the way to the left in FIG. 5), tabs 72 will be spaced out of contact with solenoid cores 35 (FIG. 6). When finger 60 is not retracted (FIGS. 7, 8), flanges 72 will either be biased by springs 70 into contact with the side of their respective solenoid cores 35 (FIG. 7), or, if core 35 has been retracted by actuation of its solenoid, aligned with the tip of core 35 (FIG. 8).

Shaft 164 carries a brush 220 (FIGS. 2-4) having fingers 220a-c (FIG. 3) arranged to move against brush plate 222 which has electrical contact strips 228, 230, 232, and 234.

Card handling assembly 240 is mounted in housing 10 and includes (FIG. 2) base plate 250, card spacers 252, 254, upper guides 256, 258, and rubber rollers 260 and 261 mounted respectively on shafts 262 and 263 supported in bracket 264. Torsion springs 266 (only one shown in FIG. 2) are connected between the shafts and brackets 264 to bias the rollers in an at rest position. Arms 270, 272 with raised ends 274, 276 extend from one side of base plate through a slot in housing 10. Base plate 250 supports metal rollers 280, 281 beneath and in light contact with rubber rollers 260 and 261. Card receiving mouth 282 (FIG. 2) is supported on module 26 adjacent assembly 240 and opening into the space between block 46 and die plate 92. Guide 283 (FIG. 1) is provided to protect arms 270, 272 and to provide for easy alignment of the card to be punched.

A single additional punch 290 is located to the right of the 40 punches 30 (FIG. 4). A separate slide 294 and solenoid 292 are provided for control of this punch. Whenever the meter is read through the probe punch 290 is allowed to punch the card, providing an indication that a probe reading was taken.

Extra space in the module (e.g., additional openings 82 not used in the present embodiment, and space for additional solenoids such as 34a) is provided for recording of data with more than digits 0-9.

In operation, a card is inserted into assembly 240 between plate 250 and guides 256, 258. The card passes into the nips between rollers 260, 261 and rollers 280, 281 respectively and rotates the former against the force of springs 266. When the card is fully inserted, it is released and rollers 260, 261 force it back until the rear edge of the card is against ends 274, 276, thus accurately positioning the card beneath the punches. Spacers 252, 254 position the card laterally.

The probe is then inserted into the readout apparatus of the meter to be read (or else dials 24 are set manually and button 25 is pressed). Four of the 16 decoding solenoids 34 are actuated, so that their cores lift out of the way of the tabs 72 of the four slides 32 respectively controlled by the actuated solenoids. Reset solenoid 64 is also actuated at this time, retracting all the slides 32 so that their tabs 72 are out of contact with the cores of solenoids 34. Solenoid 64 acts slightly before the four actuated solenoids 34, so that the four cores will not rub against the tabs when they retract. Any cores 35 that, at the end of the previous cycle, were retracted and aligned with the tabs of their respective slides, will drop past their slide tabs when solenoid 64 acts (unless, of course, they are among the cores to be actuated in the new cycle).

After 50 milliseconds all power to the solenoids is cut off. Reset solenoid 64 returns more quickly than solenoids 34, and releases the slides 32, 36 of which move forward until their

tabs hit the unretracted solenoid cores, and four of which continue to move forward until their tabs are aligned below or above the cores of the four actuated solenoids 34. These four cores then drop into contact with the respective slide tabs.

5 The punching cycle is now ready to begin, and motor 167 starts to move, retracting drawbar 150 to move roller 172 successively along cam surface portions 142, 144, and 146. At the same time, commutator brush 220 moves over brush plate 222. During the 360° cycle of brush 220 its finger 220a remains at all times in contact with ground contact strip 228. Finger 220b remains in contact with strip 230 except at gap 231 where it is located at the start of the cycle. Finger 220c starts the cycle between strips 232 and 234 and contacts them successively in that order. The effect of fingers 220b or 220c contacting strips 230, 232, or 234 is simply to connect those strips to ground, since all three fingers are part of a single piece of metal.

When roller 172 is on surface 142 (FIG. 9), punches 30 are biased by springs 200 so that shoulders 194 of punch tabs 192 are against plate 96. As roller 172 moves up surface 144, pressure pad 36, plates 114, 100, and 96, cage 110, and the punches move as a unit toward the lower part of module 26, until 36 of the punches (typified by the left-hand punch in FIGS. 9-11) contact a slide at the upper portion of neck 182. Four of the punches, typified by the right-hand punch in FIGS. 9-11, will not contact any slide; these are the punches that will punch through the card. The other 36 punches stop their downward movement and cage 110 moves downward relative to these punches, compressing their springs 200, so that their punch tabs 192 move above plate 100. As soon as these 36 punch tabs 192 clear plate 100, solenoid 104 is actuated (by contact of brush finger 220c with contact strip 232) and draws plate 100 to the left (FIG. 11), locking the tabs 192 of the four punching punches below plate 100, and locking the other 36 tabs 192 above plate 100. Roller 172 now moves to surface 146, the downward movement of the upper part of module 26 continues, and plate 100 forces the heads 180 of the four selected punches through the card.

40 By this time motor 167 has moved through half a revolution, and the direction of drawbar 150 and roller 172 reverses. Brush finger 220c moves out of contact with strip 232, deactuating solenoid 104 to return plate 100 to the right. Springs 136 return the upper portion of the module to its original position, and the punches return to the position of FIG. 9. Brush finger 220c then contacts strip 234 and the motor is stopped. The card is removed by simply lifting its front edge above ends 274, 276, so that rollers 260, 261 will eject it, completing the cycle.

50 By virtue of the arrangement of slides and punches operating friction is minimized (since the punches do not rub against the slides) and power requirements lessened. Efficient use of power and hardware is made possible by using the small individual solenoids 34 only to decode the data, all power for moving the slides coming from large solenoid 64 and springs 70.

55 The electronic circuitry employed is shown in the block diagram of FIG. 12 and the circuit diagram of FIG. 13. Insertion of the probe (or depression of button 25) closes switch 296 (or switch 298) to actuate switch sensing circuitry 300 which in turn triggers through line 301 a 50-millisecond-monostable multivibrator 304. The 50 millisecond square pulse generated by multivibrator 304 is carried through line 306 to the bases of transistors 309 and 310 in power amplifier 308 for actuation of solenoid 64, through line 307 to motor control flip-flop 312, and through line 311 to steering gate 324 which controls power amplifiers 316, 320 for actuation of the selected solenoids 34.

60 70 Flip-flop 312 goes into its set position at the end of the 50-millisecond pulse and starts the motor 167 through amplifier 332. Brush finger 220b contacts strip 230 to ground the collectors of transistors 302 and 303 in generator 304, disabling the generator circuitry from firing again until the motor stops.

75 When brush finger 220c grounds strip 232 amplifier 340 is ac-

tuated, and in turn actuates solenoid 104. Flip-flop 312 is reset when brush finger 220c contacts strip 234, stopping the motor 167.

When switch 296 is closed upon insertion of the probe, the emitter of transistor 325 of gate 324 is grounded through line 326, actuating power amplifier 320 through line 321. Power is transmitted from amplifier 320 through cable line 16x to the probe and to the meter data source on the house (a suitable BCD data source is described in U.S. Pat. No. 3,369,746). Sixteen data lines 16a-p in cable 16 carry the data to 16 identical corresponding amplifiers 328a-p (only two shown in FIGS. 12, 13) which in turn control the 16 solenoids 34a-34p. The two remaining lines in cable 16 connect the circuitry to switch 296 located in the probe. When the probe common is activated, amplifier 328q is activated through line 16q to actuate solenoid 292.

Similarly, when switch 298 is closed to indicate a manual readout, the emitter of transistor 327 is grounded through line 328, actuating amplifier 316. Power is transmitted to manual switches 24 through line 25x. Sixteen lines 25a-p carry the encoded data to amplifiers 328a-p.

Amplifiers 328a-p are mounted on boards 210, 212. Power is supplied by battery pack 18 to the circuit points marked B+ in FIG. 13. Voltage regulating circuitry 342 supplies regulated B+ current to switch sensing circuitry 300 and multivibrator 304.

The circuit elements corresponding to the block diagram of FIG. 12 are shown in FIG. 13, with dashed lines setting off the groups of elements that form the various blocks of FIG. 12. All diodes shown are TS-05. All NPN transistors are 2N3414 and all PNP transistors are 2N3702, except as otherwise indicated in FIG. 13. Standard notation is used in FIG. 13 for the identity and values of the various circuit elements.

We claim:

1. Apparatus for recording data, comprising:

a frame;

a plurality of recording elements mounted in said frame for movement parallel to a first axis between retracted positions and recording positions;

a plurality of slides mounted in said frame for movement parallel to a second axis generally transverse to said first axis;

said slides being arranged in a plurality of stacks extending along said first axis;

said slides having openings therein arranged so that in certain positions of said slides some of said openings are aligned with a said recording element to permit its passage through a said stack of slides to its said recording position and others of said openings are nonaligned to prevent passage of at least a portion of another said recording elements through said stack, said recording elements contacting said slides only when said nonaligned openings prevent said passage, each said opening being larger than the cross section of any said recording element associated therewith for passage therethrough, and a portion of each said recording element when in said retracted position extending through at least an opening in one slide without contacting said slide; and

actuators for said slides and said recording elements.

2. Apparatus for recording data, comprising:

a frame;

a plurality of recording elements mounted in said frame for movement parallel to a first axis between retracted positions and recording positions;

a plurality of spring biased slides mounted in said frame for movement parallel to a second axis to selectively control the movement of said recording elements in accordance with said data;

at least one power solenoid mounted to move said slides against said spring biasing parallel to said second axis; additional solenoids mounted to control the positions of said slides in accordance with said data;

members each having a first position in the path of said movement of a said slide parallel to said second axis and a second position out of said path, said additional solenoids being in respective operative control of said members; and

an actuator for said recording elements.

3. Apparatus as set forth in claim 2 wherein said first and second positions of each said member are spaced parallel to said first axis.

4. Apparatus as set forth in claim 2 wherein said each slide has a tab extending generally transverse to said second axis, a said member is provided corresponding to each said tab, and each said member when in its first position is in the path of movement of said tab parallel to said second axis.

5. Apparatus as set forth in claim 3 further comprising electrical circuitry including said power solenoid and said additional solenoids, said circuitry being arranged so that in a first condition of said apparatus said power solenoid and selected ones of said additional solenoids are actuated, said members corresponding to said actuated additional solenoids being respectively out of said paths of said corresponding tabs, said members corresponding to the nonactuated additional solenoids being respectively in said paths of said corresponding tabs, and in a second condition of said apparatus all said solenoids are deactuated and said tabs corresponding to said originally actuated additional solenoids are adjacent said members operatively controlled by said last mentioned solenoids thereby preventing said members from reaching their said first positions.

6. Apparatus as set forth in claim 2 wherein said power solenoid is larger than each of said additional solenoids.

7. Apparatus for recording data, comprising:

a plurality of recording elements mounted in said frame for movement parallel to a first axis between retracted positions and recording positions;

a plurality of slides mounted in said frame for movement parallel to a second axis generally transverse to said first axis;

said slides being arranged in at least one stack extending along said first axis;

said slides having openings therein arranged so that in certain positions of said slides some of said openings are aligned with a said recording element to permit its passage through said stack of slides to its said recording position and others of said openings are nonaligned to prevent passage of at least a portion of another said recording element through said stack, said recording elements contacting said slides only when said nonaligned openings prevent said passage; and

actuators for said slides and said recording elements; and

said slides being spring biased in one direction of said second axis,

at least one power solenoid being provided to move said slides in the other direction of said axis,

additional solenoids being provided to control the positions of said slides in accordance with said data, said additional solenoids being in respective operative control over members each having a first position in the path of movement of a slide parallel to said second axis and a second position out of said path.

8. Apparatus as claimed in claim 2 wherein a single power solenoid is mounted to control all of said slides.

9. Apparatus for recording data comprising:

a frame;

a plurality of recording elements mounted in said frame for movement parallel to a first axis between retracted positions and recording positions;

a plurality of slides mounted in said frame for movement parallel to a second axis to selectively control the movement of said recording elements in accordance with said data;

a pressure pad for driving said recording elements to their recording positions;

a member having oblique surface portions mounted on said pressure pad; and
 at least one roller driven by a motor along said oblique surface portions to drive said pressure pad.

10. Apparatus for recording data, comprising:

5 a frame;

a plurality of recording elements mounted in said frame for movement parallel to a first axis between retracted positions and recording positions;

10 a plurality of slides mounted in said frame for movement parallel to a second axis to selectively control the movement of said recording elements in accordance with said data;

actuators for said slides and said recording elements; and

15 a card handling assembly for receiving a card upon which said data is to be recorded, comprising:

a base,
 at least one roller mounted for rotation adjacent said base,
 a spring operatively biasing said roller about its rotational axis, and
 a card abutment spaced from said rotational axis along said base,
 said roller being arranged to contact said card when said card is inserted into said assembly along said base in the direction away from said abutment.

11. Apparatus as set forth in claim 10 further comprising at least a second roller mounted in said base adjacent and in contact with said one roller, whereby said rollers provide a nip to receive said card.
